UNITED STATES PATENT OFFICE

FRANK LA BARRER, OF BALTIMORE, MARYLAND

DISPLAY APPARATUS

Application filed March 26, 1929. Serial No. 350,018.

This invention relates to improvements in display apparatus.

The primary object of this invention is the provision of display apparatus.

5 A further object of the invention is the provision of a merchandise display device, by means of which clothing and other articles of merchandise may be continuously and efficiently displayed in a moving relation, so 10 that the same may be thoroughly viewed in an attractive manner to spectators.

A further and important object of this invention is the provision of an improved display device, which consists of a plurality of 15 merchandise supporting members movably positioned remote from each other, and embodying a cooperative illuminating and curtain screening arrangement which will permit the merchandise on the movable members 20 to be alternately displayed through a single viewing opening.

Other objects and advantages of this invention will be apparent during the course of the following detailed description.

25 In the accompanying drawings, wherein similar reference characters designate corresponding parts throughout the several views,

Figure 1 is a fragmentary plan view, partially diagrammatic, showing the relation of the improved cabinet and associated merchandise display details.

Figure 2 is a front elevation, partly in section, showing the manner in which a model 35 or article of merchandise may be positioned in the cabinet and viewed in an efficient reflected relation by spectators.

Figures 3 and 4 are sectional views taken substantially on their respective lines in 40 Figure 1 of the drawings, these views being on an enlarged scale.

Figure 5 is a fragmentary sectional enlarged view taken substantially on the line 5-5 of Figure 4.

45 Figure 6 is a fragmentary plan view showing one of the movable turn tables upon which a plurality of articles of merchandise may be positioned in a movable relation thereon; the view illustrating the details of 50 the rotatable turn-table arrangement.

Figure 7 is a sectional view taken through a detent utilized in connection with the holding of the turn-tables against rotation.

Figure 8 is a side elevation of the socket in 15 the turn table into which the detent of Figure 7 engages.

Figure 9 is a view showing a latch for holding the detent inoperative.

Figure 10 is a view showing contacts which 30 may be carried by stationary and movable portions of the improved merchandise display device, forming a switch for controlling a circuit.

Figure 11 is a sectional view taken substantially on the line 11-11 of Figure 1, said 65 view being on an enlarged scale.

Figure 12 is a fragmentary sectional view taken substantially on the line 12-12 of Figure 11.

70 Figure 13 is a horizontal sectional view taken through portions of the improved device, showing a plate glass reflecting member and a cooperative opaque screen operating upon an endless chain or carrier in a novel relation to permit the efficient reflection.

75 Figure 14 is a diagrammatic view showing the wiring diagram of the various circuits of the details of the improved device.

In the drawings, wherein for the purpose of illustration is shown only a preferred embodiment of the invention, the letter A may generally designate the improved merchandise display device, which may comprise a cabinet or enclosure B, divided by a partition 80 C into compartments D and E, wherein merchandise supporting main turn-tables F and G are rotatably positioned. Means H is provided in the casing or cabinet B, forming an opening or passageway in which the spectator looks, for observing the merchandise on the turn-tables F and G; the latter being observed direct, and the former thru the intermediary of reflecting equipment K. Cooperatively controlled illuminating means L 85 and M are provided in the compartments D and E respectively for the merchandise supporting devices F and G.

90 The casing construction B of the improved device preferably comprises a supporting floor or platform 20, which may be a per- 95

manent part of a building structure, or supported upon trestles or other supports 21. Upstanding studding or posts 22 may be provided, having horizontal overhead beams or supports 23 connected therewith if desired; the posts 22 being arranged in a four-walled arrangement, and being adapted to receive opaque fabric or other wall forming material thereupon and over the horizontal beam supports 23, to provide a front wall 24; side walls 25 and 26; a rear wall 27, and a roof wall 28, all preferably opaque and interiorly finished in black, although this is merely a preferred arrangement.

15 The compartments D and E are preferably partitioned by the wall C, which is preferably of fabric or any other approved wall forming material, diagonally disposed in the cabinet or casing, from the corner location of the 20 walls 25 and 27 at approximate angles of 45° with respect thereto, to a location adjacent the juncture of the front wall 24 and other side wall 26. This defines the compartments 25 D and E, which while they are shown of unequal size, may be approximately equal in dimension.

10 The means H forming the view opening or 30 passageway consists of curtains or walls 31 and 32, of opaque material, extending normal to the front wall 24, in spaced relation; the front wall 24 having the opening 33 therein, of any approved width and height, although sufficient to display therein the full height and width of a living person of average 35 height. The walls 31 and 32 intersect thru the partition wall C, and at this intersection the reflecting means K is positioned; the walls 30 and 31 terminating in spaced relation within the compartment E. In the wall 31 40 within the area of the compartment D, the same is provided with laterally extending spaced walls 34 and 35, defining a lateral passageway 36 which directly faces the diagonally positioned reflecting means K, and which walls 34 and 35 terminate in the compartment D in spaced relation facing the means F.

15 The merchandise supporting and receiving devices G and F are in the nature of turn-tables supported in openings 40 in the platform 20. Each of the turn-tables F and G includes a disc-shaped circular body 42, provided with depending rollers 43 about the margin thereof, on the lower surface thereof, which ride upon the inwardly flanged end of an L-shaped trackway 44, which is bolted or otherwise secured at 45 to the bottom of the base 20, annularly about the opening 40, by means of a substantially U-shaped depending 50 yoke or bracket 46, which extends diametrically across and below the opening 40.

55 Means is provided to rotate each body 42 of the turn-tables, which consists, as shown in Figures 3 and 4 of the drawings, of a vertically depending stub shaft 47, bolted at 48

to the lower portion and axially of the disc 42; the lower end thereof having a bevel gear or pinion 49 thereon. A motor 50 is carried by the yoke 46 of the respective turn-table F or G, as the case may be, the shaft 51 of which has a worm 52 meshing with a worm 70 gear 53 which is keyed upon a shaft 54, which, as shown in dotted lines in Figures 6, has a gear 55 that meshes with the pinion or bevel gear 49 above described. This structure can be clearly understood from Figures 3, 4 and 6 of the drawings.

75 The motors 50 of the rotatable devices F and G are cooperatively controlled as will be subsequently mentioned.

80 Each of the turn-table devices F and G, and the turn-table body 42 thereof, are provided with circular openings 60 and 61, as shown in Figure 3 of the drawings, at diametrically opposed sides of the center thereof, rotatably receiving therein merchandise supporting turn-tables 63 and 64 respectively, and rotatable therein upon supports 65 which are carried by brackets 66 attached to and beneath the respective turn-table bodies 42, as shown in Figure 3. Individual means are provided for rotating the tables 63 and 64, consisting of motors 70, supported on respective brackets 66. These motors 70 are provided with shafts 71 having worm gears thereon, designated at 72 in the drawings, which mesh with worm gears 73 of the shafts 74, shown in Figure 5; the shafts 74 driving the depending stub shafts 76 of the respective minor turn-table 63 and 64, by means of bevel gears 78, shown in Figure 5.

85 The turn-table devices F and G are so positioned that the merchandise supporting turn-tables 63 and 64 thereon may be selectively aligned with the passageways of the device H which respectively face in the compartments D and E, it being noted that the plane of the wall 31 about diametrically intersects the disc G, and that the plane of the wall 35 substantially diametrically intersects the turn-table device F, so that in the case of the turn-table device G, only one of the minor turn-tables 63 or 64 thereof may be aligned with the passageway between the walls 31 and 32, and in the case of the turn-table device F only one of the minor turn-tables 63 or 64 may be aligned in the passageway between the walls 34 and 35.

100 Referring to the means K, the same preferably includes a sheet of plate glass 80, carried detachably in a frame 84 across an opening provided in the partition wall C, in that portion which intersects the passageway between the walls 31 and 32 above mentioned. An observer standing exteriorly of the cabinet B facing the opening 33 may look down the passageway therethrough and through the transparent plate glass 80 and readily observe any merchandise supported on the respective minor turn-table of the turn-table 105 110 115 120 125 130

device G which happens to be facing the passageway between said walls 31 and 32; it of course being understood that the merchandise as thus positioned is readily seen by the 5 illumination from means M.

Of course, an observer at the opening 33 cannot directly see merchandise upon the turn-table device F. In order to permit such, however, the means M is dimmed or cut off 10 altogether to darken the compartment E and the compartment D is illuminated by the means L, which permits a reflection of the merchandise on that portion of the minor turn-table of the turn-table device F which 15 happens to be facing the passageway 36 to be observed in a reflected manner from the plate glass 80. Under the latter circumstances to assist in proper reflection of the merchandise from the plate glass 80, it is preferred to 20 place an opaque screen rearwardly of the same. This screen must be so placed that it will be removed upon switching of illumination from the compartment D to the compartment E, in order that the merchandise 25 on the turn-table arrangement G may be observed, since the merchandise upon the turn-table devices F and G are alternately displayed to the observer. To this end, vertical shafts 82 and 83 are supported at opposite 30 sides of the passageway defined by walls 31 and 32, at the outer sides of said walls, and preferably rearwardly of the partition C. These shafts 82 and 83 are carried at their 35 upper ends by a horizontal top beam 84, braced by diagonal braces 86, as shown in Figure 11. The shafts 82 and 83 at their upper ends are provided with sprocket wheels 88, over which an upper sprocket or endless chain 88 is provided, and the lower ends of 40 said shafts 82 and 83 are provided with sprocket wheels 87 having a sprocket endless chain 89 trained thereover. Between the upper and lower sprocket chains 88 and 89 are disposed two preferably flexible fabric 45 opaque or non-transparent curtains 90 and 91, each of which, in length, is equivalent to slightly more than one-half the distance between the axes of the shafts 82 and 83. This arrangement is shown in Figure 13, and the 50 curtains 90 and 91 are so secured to the sprocket chains that the edges thereof are spaced the same distance along the endless sprocket chains. With such an arrangement, the endless chains need be driven in one 55 direction only, and the passageway between the walls 31 and 32 at the rear of the transparent plate glass 80 will be alternately covered by the opaque curtains 90 and 91. 60 In Figure 13 it is shown that the opaque curtains 90 and 91 are overlapped to cover the rear of the plate 80, and in Figure 1 said curtains or screens 90 and 91 are traveling about the shafts 82 and 83, so as to not obstruct the passageway at the rear of the plate 65

80, for a purpose to be more fully hereinafter set forth.

The endless chains or sprockets 88 and 89 are rotated by means of a motor 93 connected through suitable gearing 94, with the shaft 83, as shown in Figures 11 and 12. The motor 93 need be driven in one direction only, in order that the curtains 90 and 91 may alternately shut off and open the passageway between the walls 31 and 32. 75

The illuminating means L consists of a series of foot lights 100, set within a depression in the floor or base 20 across the space between the walls 34 and 35, remote from the plate glass 80, where the passageway 36 opens into the compartment D. Vertically disposed illuminating devices 101 and 102 are provided at each end of the series of lights 100, positioned to converge the rays thereof, and to one or the other of the minor tables 63 and 64 in a line axially of the passageway 36. With the opaque screen formed by the curtains 90 and 91 positioned to the rear of the plate glass 80, the latter will act as a mirror and reflect therefrom to observers standing at the opening 30, the image of any merchandise which is illuminated in the compartment D by means L, on either minor turn-table 63 or 64 which faces the passageway 36. Of course, the turn-table device F may be rotated to alternately place merchandise on the minor turn-tables 63 and 64 in such position. 90

The illuminating means M consists of a series of foot lights 105 arranged directly across the space between the walls 31 and 32, where the passageway 106 between said walls opens into the compartment E. Vertically disposed illuminating devices 107 and 108 are positioned to converge the rays of light therefrom, onto a portion of the turn-table device G which immediately faces axially of the passageway 106. It should be noted, as an important feature, that the illuminating means M is not as intense as the illuminating means L, and one way of obtaining this effect 100 is to provide more lights in the illuminating means L, although the same results might be accomplished by variation in candle power. 105

If desired, decorative screens 110 and 111 may be positioned on the interior of the walls 27 and 25 respectively, in facing relation with the openings of the passageways 106 and 36 respectively, thru the compartments E and D respectively, for the obvious reason of permitting spectators and observers to view only an attractive display, which may be placed in an environment most suitable for the class of merchandise on display. 110

Referring to the diagrammatic representation of Figure 14, current is supplied from a generator or other source 120, from which a line 121 leads off, wherein a main switch 122 is positioned. A circuit making and breaking device 123 is provided, which may be either manually or automatically controlled, 125 130

which consists of a rotatably supported switch arm 124, directly connected in the line 121. Contacts 125 and 126 are diametrically opposed from the pivot axis of the switch arm 124, for alternate engagement by the latter; the same being respectively connected in circuits 127 and 128, wherein are positioned the motors 50 which control the rotation of the turn-table devices F and G respectively. The circuits 127 and 128 of course receive current from the generator 120. So that the circuits 127 and 128 may be independently controlled, it is preferred to provide switches 129 and 130 respectively there-in, for purposes to be subsequently mentioned.

The controller switch mechanism 123 furthermore includes arcuate contacts 134 and 135, positioned at diametrically opposed sides of the pivot center of the switch arm 124, and for switch engagement by the latter. The said contacts 134 and 135 are disposed in circuits 137 and 138, wherein the minor turn-table operating motors 70 of the turn-tables G and F are respectively interposed, as will be subsequently mentioned. Of course, these circuits 137 and 138 include the generator 120 as a portion thereof. The curtain controlling motor 93 is disposed in a circuit 140, one lead wire of which extends to the circuit controller 123, and has a pair of diametrically disposed switch contacts 141 and 142 therein, for alternate engagement by the switch arm 124. The contact 142 is intended to put the motor 93 in operation, when the switch arm 124 engages the same, to move the opaque curtains 90 and 91 from an open to a closed position across the passageway 106, and the engagement of the switch arm 124 with the contact 141 will cause a movement of the opaque curtains 90 and 91 so as to move them from a closed to an open position with respect to said passageway 106.

From Figure 14 it can be seen that each of the minor turn-table motors 70 is disposed in an open circuit upon the support therefor, including a pair of contacts 160, as shown in Figure 14. These contacts 160 are each of the nature shown in Figure 10, insulated, as shown at 161 from the bracket 66 which respectively supports the same. Likewise, each of the circuits 137 and 138 are opened to provide a pair of contacts 162, which may be engaged by the contacts 160 to close the said circuits 137 and 138, as the case may be, when the turn-table devices F and G are rotated to the proper positions. This is well shown in Figure 14 of the drawings, and is obviously an arrangement which will permit the minor turn-tables 63 and 64 to rotate as they are moved into position for display. The illuminating devices L and M have a common rheostat P, which includes a movable pivoted arm 165 connected by a line 166 with one terminal of the generator 120. A line 167 extends from

the other terminal of the generator, wherein the lamps of the illuminating means L are positioned, and this line 167 is connected to one end of the resistance coil 170 of the rheostat P. Another circuit line 172 is connected to the same terminal of the generator 120 as the line 167 above described, but at its opposite end it is connected to the opposite end of the rheostat resistance coil 170. In this manner the current from the generator 120 may be employed to gradually switch the current from the illuminating means L to the illuminating means M, and vice versa, to vary the intensity of illumination, and finally shut off one of said illuminating means, while fully illuminating the other. This is a selective arrangement.

Detent devices 170' are provided in connection with each of the turn-table bodies 42 to prevent rotation thereof when in definite position, and also in connection with each of the minor turn-tables 63 and 64 of the turntable devices F and G. The detents 170' are best illustrated in Figures 7, 8, and 9, each consisting of a detent body 171 reciprocably supported in a suitable recess 172 in a portion of the structure facing the periphery of the respective turn-tables; spring urged at 174 against the periphery of the turn-tables, for seating in sockets 175 provided therein. The sockets 175 are provided at one point only on the periphery of the minor turn-tables 63 and 64, but are preferably provided at diametrically opposed locations on the periphery of the major turn-table bodies 20, as shown in Figure 6, to alternately position the minor turn-tables 63 and 64, in display position. Means 178 is provided to manually withdraw the detent body 171 from the socket 175, and pawls 179, best shown in Figure 9, are provided, pivoted at 180, and overbalanced at their ends 181, to normally engage against the detent bodies 171. The forward end of each of the detent bodies 171 is reduced, providing a shoulder 182 at its juncture with the squared or polygonal portion 183 which fits in the recess 182, as shown in Figure 9, and the weighted end 181 of the detent 170' will fall upon the reduced end of the detent body and engage against the shoulder 182 to prevent the spring 174 from urging the detent into the socket 175. The opposite end of the pawl 179 from the end of greater weight is provided with a sloping edge 185, which a pin 186 on the periphery of the respective turn-table cooperating therewith is adapted to engage, to trip the pawl 179 and permit the spring 174 to urge the detent 170' against the periphery of the turn-table; the latter rotating until the detent engages in a socket 175, at which time the turn-table stops and is held in position against rotative movement until the detent is manually released, in a manner which is perfectly apparent.

The operation of the device will be apparent from the foregoing description. The observer's stand is at the front wall looking into the opening 33 axially of the passageway 106. With the opaque curtains 90 and 91 removed from the rear of the transparent plate glass 80, the lamps are on in the illumination M, and the lamps of the means L are "off", as regulated by the controller 165 above described. This enables the observer to see through the transparent plate 80 directly on the article of merchandise supported on the turn-table 63 or 64, which happens to be exposed axially of the passageway 106, and the said minor turn-table 63 or 64 which is so exposed slowly rotates, by reason of the fact that the motor 70 thereof is in the circuit 137, as shown in Figure 14. The observer, of course, sees the entire article of merchandise, during its course of rotation. As soon as it has completed a rotation, the detent 170' therefor drops into its socket 175, and at this time the observer will see a change in scene and illumination slowly taking the place, due to the fact that the illumination M is being closed off, and the lamps of the illuminating means L coming on. During this interval both of the turn-table devices G and F are stationary, and the opaque curtains 90 and 91 move into the position shown in Figure 13. As the lamp means L is fully illuminated the article of merchandise on the minor turn-table of the turn-table device F which faces the passageway 36 is set into rotation, by the circuit arrangement above described, and the same is reflected to the observer from the diagonally positioned plate glass 80, which acts as a mirror in reflecting a true image of the rotating article of merchandise. During this interval the operator has released the detent 170' of the turn-table G and permitting the turn-table to rotate to 180° to position the other minor turn-table in line with the passageway 106, with an article of merchandise supported thereon in position to be rotated as soon as the article of merchandise on the minor turn-table which faces the passageway 36 has completed its revolution. Thus, the illumination is switched back and forth between the compartments D and E, and the turn-table devices F and G alternately rotated to alternately display the article of merchandise on each of the minor turn-tables thereof thru the passageways 36 and 106, to the observer looking into the opening 33. Live models, dummy models, and other articles of merchandise either larger or smaller may be displayed. The intensity in the illuminating means L is multiplied over that of the intensity of the illuminating means M, due to the fact that the former must act to reflect the merchandise to the observer, while the latter does not act in this manner.

large turn-table a fashion subject may be positioned, dressed, in say, hat, coat, handbag, parasol, and the like, and on the opposite small turn-table of the same major turn-table, the subject may be dressed in lingerie. In the other compartment one of the subjects may be dressed in ordinary house or street dress, and opposite to her in the same compartment on the other turn-table may be placed a girl wearing a bathing suit, in position to be visible to the spectator succeeding the observance of the lingerie display. Any number and variety of such alternations and changes may be made without stopping the display or detracting from the interest of the spectators.

Various changes in the shape, size, and arrangement of parts may be made to the form of invention herein shown and described, without departing from the spirit of the invention or the scope of the claims. 83

I claim:

1. In a display device the combination of an enclosure having an observer's opening therein, a display device positioned for displaying objects thereon directly to an observer looking through the observer's opening, a second display device in the enclosure, reflecting means for reflecting an image of the objects on the second display device through the observer's opening to the observer, synchronized illuminating devices for each of the display devices, and opaque screening means synchronized with operation of the illuminating means and said display devices for shutting off the first mentioned display device to the observer upon the illumination of the second display device. 90 95 100

2. In a display device of the class described in an enclosure having a pair of display compartments therein, a single observer's opening, means providing a passageway direct from the observer's opening to a display in one of the display compartments, a second means providing a lateral passageway leading from the first mentioned passageway, reflecting means positioned in the first mentioned passageway for reflecting objects from the second display compartment thru the second passageway thru the observer's opening, means in each of said compartments positioned at the ends of the first and second passageways in the enclosure for supporting objects in facing relation with respective passageways, means for selectively illuminating said display compartments, and opaque curtain means operable in the first mentioned compartment to shut off vision therefrom when the second mentioned compartment is illuminated for display purposes.

125

136

3. In a display device an enclosure having an observer's opening and a passageway leading therefrom to a compartment in the enclosure, a lateral passageway leading off from the first mentioned passageway and out of direct alignment with the observer's opening, a transparent plate of glass positioned di-

agonally across the first mentioned passageway for reflecting objects aligning with the second mentioned passageway thru the observer's opening, objects on display in the 5 compartment at the end of the first mentioned passageway being directly visible thru said transparent plate of glass and thru the observer's opening, and opaque screening means operable across the first mentioned passageway 10 between the transparent plate glass and the display compartment at the end of said first mentioned passageway.

4. In a display device an enclosure having an observer's opening and a passageway leading 15 therefrom to a compartment in the enclosure, a lateral passageway leading off from the first mentioned passageway and out of direct alignment with the observer's opening, a transparent plate of glass positioned 20 diagonally across the first mentioned passageway for reflecting objects aligning with the second mentioned passageway thru the observer's opening, objects on display in the compartment at the end of the first mentioned 25 passageway being directly visible thru said transparent plate of glass and thru the observer's opening, opaque screening means operable across the first mentioned passageway between the transparent plate glass and the 30 display compartment at the end of said first mentioned passageway, and means for alternately and selectively illuminating the respective displays in said enclosure.
